UNITED STATES PATENT OFFICE

FRANCIS H. TREAT, OF BELLEVUE, OHIO, ASSIGNOR OF ONE-HALF TO DUFF PATENTS COMPANY, INC., OF PITTSBURGH, PENNSYLVANIA, A CORPORATION OF PENNSYLVANIA; GRACE D. TREAT ADMINISTRATRIX OF SAID FRANCIS H. TREAT, DECEASED

GAS PRODUCER

Application filed December 2, 1924. Serial No. 753,433.

The present invention relates to gas producers, and more particularly to gas producers of the type having mechanical means for supplying fuel to the fuel bed and for 5 agitating the fuel bed.

Heretofore, in the operation of gas producers in which the fuel is supplied to and distributed over the fuel bed mechanically, it has been the practice to supply the moisture for the blast in the form of steam generated exteriorly of the gas producer. The 10 heat required for producing this steam amounted to about ten per cent of the total heat consumption in the operation of the gas producer. The water for cooling the agitators and the feeding and distributing means, as well as the water for the water seals at the 15 top of the producer, when it became heated to such an extent that it was no longer effective for cooling, was allowed to run to waste.

By the present invention I provide a gas producer of the mechanically operated type having provision for supplying the moisture to the blast by drawing the air for the blast 20 over the surface of the cooling water. This not only serves to maintain the temperature of the cooling water low, and thereby reduce the wastage of water by increasing the time interval between changes of the cooling water, but also eliminates the necessity for producing steam by external heat and mixing 25 such steam with the air supplied to the blast. This method of operation materially reduces the operating cost of the producer. In the 30 specific embodiment of the invention herein-after described I provide an exhaust fan which draws the air in over the cooling water at the top of the gas producer and supplies it, laden with moisture, to the tuyères or grate members.

In the drawings:—

Figure 1 is a vertical sectional view through 35 a gas producer embodying a preferred form of the present invention;

Figure 2 is a vertical sectional view of the 40 gas producer taken on a plane approximately at right angles to the plane of the section shown in Figure 1;

Figure 3 is a plan view, on a larger scale,

of the rotatable fuel feeding and agitating top of the gas producer;

Figure 4 is a plan view of the rotary distributor forming a part of said rotary top;

Figure 5 is a vertical section on the line 55 V—V of Figure 4;

Figure 6 is a plan view of the rotary distributor with its cover plate removed;

Figure 7 is a view, partly in section and partly in elevation, of the parts shown in 60 Figure 6;

Figure 8 is a detail view partly in section and partly in elevation, on a larger scale, of one of the agitators;

Figure 9 is a plan view of the scraper member 65 and guard ring carried by the upper end of the fuel chute, and

Figures 10 and 11 are, respectively, a plan view and side elevation of the motor and fan arrangement for supplying the blast. 70

Referring to Figures 1 and 2, the gas producer constituting the illustrated embodiment of the present invention comprises a producer body in the form of a metal shell 2 having a suitable gas off-take 3, the body 75 and off-take having linings 4 and 5 of refractory material. The body is supported by means of columns 6 of which only one is shown, preferably of structural steel, one 80 of said columns being illustrated in dot and dash lines in Figure 2.

Beneath the shell 2 is a stationary ash pan 7 into which a mantle or apron 8, forming an extension of the shell 2, depends to a distance below the water level of the pan sufficient to provide the usual water seal. 85 Tuyères or grate members 9 project inwardly through the depending mantle or apron and are removably seated in openings therein. 90

These tuyères or grate members are uniformly spaced around the periphery of the base or shell 2 and project radially inwardly to near the axis of the shell. The construction and arrangement of the parts 7, 8 and 9 are 95 preferably the same as shown and described in my Patent, No. 1,469,399, granted October 2, 1923.

The shell 2 projects a substantial distance above its lining 4 and has an annular upwardly and inwardly sloping cover member 100

secured at its outer edge to the inner surface of the shell adjacent the top edge of the lining 4. This cover member has an annular vertical flange 11 at its inner edge, the upper edge of said flange being substantially in the same plane with the upper edge of the shell 2. The cover member 10, flange 11 and the portion of the shell 2 which projects above the cover member form an annular trough 12 10 adapted to be filled with water for cooling the upper portions of the gas producer and to provide a water seal between the body and top during relative rotation therebetween.

An outer metal shell 13 surrounds the shell 2 and projects a slight distance above the upper edge of the latter. The annular space between the shells 2 and 13 is closed at the bottom by an annular plate 14 secured to the lower edges of said shells. This annular space is divided into upper and lower annular compartments 15 and 16 by a horizontal partition 17 between the shells. The tuyères or grate members 9 communicate with the lower compartment 16.

25 The outer shell 13 has a horizontal annular cover plate 18. This cover plate is supported at its outer edge upon the upper edge of the shell 13 and is supported intermediate its edges by hollow castings 19 carried by the cover member 10. These hollow castings provide a series of poke openings 20 which are normally closed during the operation of the producer by ball valves 21.

Projecting downwardly through the central opening in the cover member 10 is a combined water reservoir and fuel feeding distributor 22, and which form a head, shown in more detail in Figures 4, 5, 6 and 7. The distributor carries an annular depending flange or apron 23 which dips into the water seal in the trough 12. Two segmental cover plates 24 and 25 are mounted on the distributor and have their straight edges parallel and spaced equal distances from a vertical plane containing the vertical axis of the distributor, thereby providing a slot 26 between said edges. The peripheral edge portions of the cover plates overhang the peripheral wall of the distributor and have an annular angle 27 secured to the under surface thereof. The vertical flange of this angle engages the upper surface of a ring gear 28 which has a vertical flange constituting a bearing for said vertical flange 55 of the angle. This ring gear is secured to the inner edge of the cover plate 18.

60 Mounted on the cover plate 24 is a motor 29 which drives a worm 30. This worm engages a worm wheel 31 mounted on a horizontal shaft 32 having its bearings in a bracket 33 projecting upwardly from the cover plate. The shaft 32 has a bevel pinion 34 on its end meshing with a bevel pinion 35 on a vertical shaft 36, the latter having a pinion 65 37 on its lower end meshing with ring gear

28, and a pinion 38 on its upper end meshing with a pinion 39 on a vertical stub shaft 40 carried by the bracket 33. Pinion 39 meshes with a pinion 41 on a second stub shaft 42 carried by the bracket, and pinion 41 meshes with a gear 43 journaled on the vertical water pipe 44, the latter being supported in a cylindrical portion 45 of the bracket 33.

70 Carried by the gear 43 is a substantially circular plate 46 adapted to receive fuel from a hopper 47, into which the fuel is delivered by a conductor 48. The fuel is prevented from spilling over the peripheral edge of the plate 46 by means of a guard ring 49. This guard ring is located adjacent the peripheral edge of the plate and has an opening between its ends into which extends a scraper 50. Referring to Figure 9, it will be seen that the scraper and the guard ring are mounted on the upper end of a chute 51. This chute is carried by the cover plate 25 and delivers the fuel through an opening 52 in said cover plate to a distributing chute 53 formed in the distributor 22. The chute 51 has a rotating pocketed fuel passing and gas sealing member 54 therein operatively connected to the shaft 32 by a flexible shaft 55.

75 It will be apparent that as the distributor 22 and parts mounted thereon are rotated in one direction by the motor and gearing arrangement described, the plate 46 will be rotated in the opposite direction, whereby the fuel carried thereby will be rotated against the scraper 50 and transferred by the latter to the chute 51. This fuel will be delivered in measured quantities by the pocketed member 54 to the distributing chute 53, which latter will distribute it uniformly to the fuel bed.

80 Supported by and depending from the top plates 56 of sleeves 57 is a pair of agitators 58. These agitators are hollow, approximately L-shaped members, the vertical legs of which have flanges at their upper ends belted to the cover plates, as shown more clearly in Figure 8, and the horizontal legs of which have each a series of depending hollow agitating fingers 59 which extend into the fuel bed and agitate the same as the distributor rotates. Brackets 60 are carried by the top plates 56 and these brackets carry nuts 61 engaged by vertical lifting screws 62 which have a bearing at their lower ends in brackets 63 carried by the cover plates 24 and 25. The sleeves 57 are located in the slot 26 between the straight edges of the cover plates 24 and 25 and guided in their vertical movements by angles 64 secured to said straight edges. The agitators pass through radial openings 65 in the bottom of the distributor 22 and sleeves 66 project upwardly from the edges of these openings and telescope loosely within the sleeves 57. It will be apparent that by turning the screws 62 the agitators can be adjusted to any desired elevation, as

illustrated in Figure 2, without withdrawing the sleeves 57 from the water-seal in the distributor 22. The combination of the agitator working over the radially arranged tuyères provides a particularly advantageous structure for controlling the fuel bed, the combustion zone and the ash conditions in the producer, as fully pointed out in my co-pending application Serial No. 147,944, filed November 12, 1926, which constitutes a continuation of this application insofar as this arrangement is concerned.

Referring to Figures 1, 2, 3 and 8, a water supply pipe 67 is connected by a swivel 68 to the upper end of the vertical pipe 44. To the lower end of this pipe is connected a short horizontal pipe 69 which has another pipe 70 connected to its outer end and extending at right angles thereto. The ends of the pipe 70 are connected by hose connections 71 to pipes 72 which extend into the hollow agitators. The cooling water flows through these pipe and hose connections into the agitators and after filling the same overflows 25 through the openings 73 in the top plates 56. These top plates are positioned below the upper edges of the sleeves 57 so that troughs 56' are formed above the plates, into which the water overflows from the agitators. 30 Each sleeve has a notch 74 (Figure 1) in its upper edge, through which the water from the troughs 56' overflows into the reservoir of the distributor 22. After substantially filling the distributor, the water overflows 35 through openings 75 (Figures 5 and 7) in the peripheral wall of the distributor adjacent its upper edge. The water overflowing through these openings fills the trough 12 above the cover member 10, and if not evaporated as fast as supplied thereto, spills over 40 the upper edge of the shell 2 into the compartment 15.

Referring to Figures 2, 10 and 11, suitably supported adjacent the outer shell 13 is an exhaust fan 76 driven by a motor 77 through a belt 78. This fan is connected, through an exhaust pipe 79, with the upper compartment 15, and through a discharge pipe 80, with the lower compartment 16. The fan 50 draws the air for the blast through the openings 81 in the cover plates 24 and 25 (Figure 4). This air is drawn over the surface of the water filling the reservoir of the distributor 22 and then through the openings 75 and 55 over the surface of the water in the trough 12. It absorbs the vapor rising from these bodies of water and, at the same time, retards the gradual rise in temperature of this water, whereby the cooling water does not 60 have to be changed as often as in the usual method of operating gas producers. The air, laden with the moisture, is forced under pressure by the fan into the compartment 16 and thence to the tuyères or grate members 9.

65 While I have shown and described a pre-

ferred embodiment of my invention, it will be understood that the invention is not limited to this illustrated embodiment thereof, but may be otherwise embodied within the scope of the appended claims without departing from the spirit of the invention.

I claim:

1. In a gas producer of the mechanical type having a body portion and a top portion, one of which is rotatable relatively to the other, an agitator carried by the top portion with means for circulating the water through the agitator, an enclosed annular water trough combined with the top and body portions and providing both a sealing and cooling medium therefor, the agitator being adapted to discharge water which has been circulated therefrom into said enclosed annular water trough, and means for circulating air over the surface of said water and expelling it into the producer.

2. A gas producer of the mechanical type wherein there is a top and a body having an annular shoulder, one of which is rotatable with respect to the other, having in combination means providing an annular water seal between the body and the top, a shell over the annular shoulder of the body and extending down around the sides of the body of the producer, said shell being spaced from the body to provide an air circulating space, a partition in the shell between the top and bottom of the producer, tuyères in communication with the space below the partition, and means for withdrawing air from the space above the partition and forcing it into the space below the partition, said top having an air intake opening in the top near its center so that air may enter the shell and circulate over water in said means providing a water seal.

3. A gas producer as recited in claim 2, characterized by the provision of a water reservoir in the top of the producer with an overflow adapted to deliver water into said means providing a water seal.

4. A gas producer as recited in claim 2, provided with a water cooled agitator in the said top and having a water reservoir in the top with an overflow adapted to deliver water to said means providing a water seal, the agitator being adapted to discharge water into the water reservoir, and the air inlet to the shell being over the top of the water holder.

5. In a gas producer, a body and a head, one of which is rotatable relatively to the other, an agitator carried by the head, an annular trough around the top of the body adapted to hold water to provide a water seal between the body and the head of the producer, means for supplying cooling water to the agitator, means for discharging water from the agitator into said trough, an outer shell enclosing said trough and the sides of

- the body, said shell being spaced away from the body and trough, and a fan having an intake leading to the space formed between the shell and the body and having a discharge passage leading into the bottom part of the producer for drawing air over the water in the trough thence through the space between the shell and the body and discharging said air into the producer.
- 10 6. The combination with a gas producer of the type having a body portion and a fuel feeding head, one of which is rotatable relatively to the other, an annular trough around the top of the body adapted to receive water for cooling the top of the producer and for forming a water seal between the fuel feeding head and body, of an outer shell surrounding the body and the trough, means for withdrawing air from the space between the shell and the producer and discharging it into the lower part of the producer, the space between the producer and the shell communicating to atmosphere through the fuel feeding head.
- 15 7. A gas producer comprising a body, a head comprising a reservoir and a fuel distributor rotatably mounted on said body, agitators carried by said head, an annular water trough around the top of said body, an outer shell embracing the walls of the body and the trough, a partition separating the space between the walls and the shell into an upper and a lower chamber, means for supplying water to said agitators, means for directing the water through the agitators, thence to the reservoir in the head from which it overflows into the annular reservoir and finally into the upper chamber between the walls of the head and the shell, means forming a water seal in the annular trough between said head and said body, said head having a restricted air opening in the top, and means for drawing air into said opening, over the water in the reservoir, the annular trough and the upper chamber and finally discharging said air into the body of the producer.

In testimony whereof I have hereunto set my hand.

FRANCIS H. TREAT.
